Primary Examiner — Cynthia Ramirez*Assistant Examiner* — Laura H Yu(74) *Attorney, Agent, or Firm* — Banner & Witcoff, Ltd.**CLAIM**

The ornamental design for a shoe, as shown and described.

DESCRIPTION

FIG. 1 is a front view of a shoe showing our design;

FIG. 2 is a rear view thereof;

FIG. 3 is a side view thereof;

FIG. 4 is a second side view thereof; and,

FIG. 5 is a rear perspective view thereof.

The oblique line shading represents a translucent or transparent appearance. The even-length broken lines show the remainder of the shoe, are directed to environment and form no part of the claimed design.
